[57] CLAIM

The ornamental design for a high frequency pulsed doppler radar antenna, as shown and described.

DESCRIPTION

FIG. 1 is a top, and front perspective view of a high frequency pulsed doppler radar antenna showing my new design;

FIG. 2 is a side elevational view thereof, rotated 45° from FIG. 1, The remaining side elevational views being the same;

FIG. 3 is a top plan view thereof, rotated 45°0 from FIG. 1; and

FIG. 4 is a bottom plan view thereof, rotated 45° from FIG. 1.
